(57) **CLAIM**

I claim the ornamental design for a neck laceration protector, as shown and described.

DESCRIPTION

FIG. 1 is a perspective view of the neck laceration protector of the claimed design;

FIG. 2 is a front elevational view of the claimed design shown in FIG. 1;

FIG. 3 is a top elevational view of the claimed design shown in FIG. 1;

FIG. 4 is a bottom elevational view of the claimed design shown in FIG. 1;

FIG. 5 is a right side elevational view of the claimed design shown in FIG. 1;

FIG. 6 is a left side elevational view of the claimed design shown in FIG. 1;

FIG. 7 is a back elevational view of the claimed design shown in FIG. 1; and,

FIG. 8 is a perspective view of the claimed design of FIG. 1, showing how it is used.

The broken lines in the drawings show unclaimed subject matter and form no part of the claimed design.
